US0D1087158S

(12) **United States Design Patent** (10) **Patent No.:** **US D1,087,158 S**
(45) **Date of Patent:** **** Aug. 5, 2025**

(54) **DISPLAY OR PORTION THEREOF WITH
GRAPHICAL USER INTERFACE**

(71) Applicant: **Apple Inc.**, Cupertino, CA (US)

(72) Inventor: **Dylan Ross Edwards**, San Jose, CA (US)

(73) Assignee: **Apple Inc.**, Cupertino, CA (US)

(**) Term: **15 Years**

(21) Appl. No.: **29/926,647**

(22) Filed: **Jan. 31, 2024**

Related U.S. Application Data

(63) Continuation of application No. 29/787,307, filed on Jun. 5, 2021, now Pat. No. Des. 1,016,090.

(51) **LOC (15) Cl.** **14-04**

(52) **U.S. Cl.**

USPC **D14/486**

(58) **Field of Classification Search**

USPC D14/485-495

CPC G06F 3/048-04897

(57) **CLAIM**

The ornamental design for a display or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display or portion thereof with graphical user interface showing the claimed design; and, FIG. 2 is another embodiment thereof.

The outer broken lines in the figures show a display or portion thereof, and form no part of the claimed design. The other broken lines in the figures show portions of the graphical user interface that form no part of the claimed design.
